Primary Examiner — Marianne Pandozzi(74) *Attorney, Agent, or Firm* — Price Heneveld LLP(57) **CLAIM**

We claim the ornamental design for a brewer, as shown and described.

DESCRIPTION

FIG. 1 is a front perspective view of a brewer of the present disclosure;

FIG. 2 is a rear perspective view of the brewer of FIG. 1; FIG. 3 is a front elevational view of the brewer of FIG. 1; FIG. 4 is a rear elevational view of the brewer of FIG. 1. FIG. 5 is a first side elevational view of the brewer of FIG. 1;

FIG. 6 is a second side elevational view of the brewer of FIG. 1;

FIG. 7 is a top plan view of the brewer of FIG. 1; and, FIG. 8 is a bottom plan view of the brewer of FIG. 1.

The broken lines in the drawing depict portions of the brewer that form no part of the claimed design.
